UNITED STATES PATENT OFFICE.

JOHN E. ARMITSTEAD, OF PROVO, UTAH.

ORE-SEPARATOR.

1,356,332.

Specification of Letters Patent. Patented Oct. 19, 1920.

Application filed November 23, 1918. Serial No. 263,888.

To all whom it may concern:

Be it known that I, JOHN E. ARMITSTEAD, a citizen of the United States, residing at Provo, in the county of Utah and State of Utah, have invented a new and useful Ore-Separator, of which the following is a specification.

This invention has reference to ore separators, and its object is to recover metal 10 from quartz or gangue by either flotation or precipitation or both without waste of any chlorid values that the ore may contain.

The invention provides means whereby the water or other liquid employed may be 15 used repeatedly until it ultimately becomes too slimy for further use, when the liquid may be drawn off into a container as fresh liquid is turned on. The means employed comprise, among other things, a concentration tube or cylinder associated with other ore precipitation tubes or cylinders, all having conveyer coils arranged to carry the gangue or pulp through the tubes or cylinders, provision being made for recovering 20 the precipitates and the floating material with the ultimate return of the liquid employed to a receiving tank from which the liquid is again directed through the apparatus.

The invention will be best understood from a consideration of the following detailed description taken in connection with the accompanying drawings forming part of this specification, with the understanding, 25 however, that the invention is not confined to any strict conformity with the showing of the drawings but may be changed and modified so long as such changes and modifications mark no material departure from 30 the salient features of the invention as expressed in the appended claims.

In the drawings:

Figure 1 is a side elevation, with some parts broken away and in section, of a portion 35 of an ore concentrator embodying the invention.

Fig. 1^a is a view similar to Fig. 1 and forming a continuation of the apparatus therein shown.

Fig. 2 is a plan view with some parts in section, of the structure shown in Fig. 1.

Fig. 2^a is a plan view of the structure shown in Fig. 1^a, with some parts in section.

Fig. 3 is a longitudinal vertical section, 55 on a larger scale than the preceding figures, of a precipitation tank for the final treatment of the material leaving the conveyers.

Fig. 4 is a section on the line 4-4 of Fig. 1 but omitting distant parts.

Fig. 5 is a longitudinal diametric section through a yieldable joint between the meeting ends of the innermost or main conveyer tubes or cylinders.

Fig. 6 is a section on the line 6-6 of Fig. 5 showing a baffle but omitting certain other parts.

Fig. 7 is a side elevation, partly broken away and in longitudinal section, of the discharge-end of a triple tube construction 70 forming part of the invention.

Fig. 8 is a section on the line 8-8 of Fig. 7, omitting distant parts.

Fig. 9 is a section on the line 9-9 of Fig. 1 drawn on a larger scale and omitting distant parts.

Referring to the drawings, there is shown a main frame composed of uprights 1, longitudinal beams 2, 3 and tanks 4, 5 supported by and joining members of the main frame.

Constituting a continuation of the tank 5 is another tank 6, containing alternately arranged baffles 7 and a discharge tube or pipe 8, for the final treatment of the liquid reaching it.

Above one end of the tank 5 and extending lengthwise of said tank for an appropriate distance is an inclined tube or cylinder 9 having exterior circumferential guide rings 10 near opposite ends. The cylinder or tube 9 at points close to the respective guide rings is carried upon supporting rollers 11, best shown in Fig. 4, these rollers being in turn carried by saddle bars 12 fast to beams 13 extending lengthwise of the cylinder or tube 9.

The beams 13 and cylinder 9 have an inclination toward the receiving end of the cylinder 9 and the corresponding ends of the beams 13 are supported by a yoke or hanger 14 carried by a screw rod 15

extending through a bar 16 carried at the ends by brackets 17 fast to neighboring posts or uprights 1 of the main frame. A hand

wheel 18 with an appropriately threaded hub 19 applied to the threaded rod 15 forms a convenient means whereby the high end of the tube or cylinder 9 may be moved up and down and the inclination of the tube 9 be

80

85

90

95

100

105

thereby adjusted. The other end of the cylinder or tube 9 is hingedly supported by hangers 14^a carried by pivot pins 14^b mounted on the adjacent uprights 1 at about the height of the top of the hinged end of the tube 9, as best shown in Fig. 4.

The inner wall of the tube 9 is provided with helical ribs 20, preferably though not necessarily in triplicate, so that the ribs are 10 relatively close together but at the same time of relatively long pitch. These ribs serve as conveyer ribs for material lodged between them and the direction of rotation of the tube 9 is such that the material is carried 15 from the lower portion of the tube toward the upper portion thereof and ultimately escapes from the upper end of the tube, which end is open. The tank 5 immediately beneath the open upper end of the tube 9 is 20 provided with a receptacle 21 normally closed by a gate 22 so that the discharge from the upper end of the tube 9 collecting in the receptacle 21 may be removed therefrom, from time to time, by opening the 25 gate 22.

Leading into the upper end of the tube 9 is a pipe 23 coming from a charging hopper 24 into which pulverized ore or gangue is fed, and also leading into the upper end 30 of the tube 9 is a jet pipe 25 continuing through the tube for the greater portion of its length and provided with perforations 26 so that water or other liquid flowing through the pipe 25 is delivered in jets into 35 the tube 9 to wash away the gangue from the heavier metals which are deposited on the inner bottom wall of the tube 9 between the ribs 20. The metals thus washed free from other matters are conveyed by the ribs 20 to the 40 upper end of the tube 9 and fall therefrom into the receptacle 21. The pipe 25 is provided with a valve 27 whereby the flow of liquid into and through the pipe may be controlled.

Continuing through the separator from the lower end of the tube 9 to about the other end of the tank 5 is a group of concentric tubes 28, 29, 30. The tube 28 is of a diameter corresponding to the tube 9 and 50 forms a continuation thereof. The tube 28 abuts the tube 9 but at a slight angle thereto, the tube 28 being rotatable about a substantially horizontal longitudinal axis, while the tube 9 slants at a small angle to the 55 horizontal and inclines away from the tube 28. The lower end of the tube 9 is provided with an inwardly directed flange 31 and the adjacent end of the tube 28 has a similar in-turned flange 32. The flanges are annular 60 flanges and the flange 31 is provided with a tubular extension 33 so arranged and of such axial length as to at all times project through the flange 32. The tube 9 carries a lock member 34 entering between ears 35 on 65 the tube 28. The lock member 34 is in the

form of a pivoted finger having an elastic extension 36 tending to maintain the finger between the ears 35 in spite of changing relations of the adjacent ends of the tubes 9 and 28. The arrangement is such that the tube 9 may rotate about a slanting axis and the tube 28 may rotate about a horizontal axis without pulling the tubular flange 33 from projection through the flange 32, the finger 34 imparting motion from one tube to the other so that when one tube is rotated by power the other tube participates in the 70 rotational movements. Close to the flange 32 the tube 28 is provided with an annular baffle 37, such baffle being spaced from the inner wall of the tube 28 by legs or projections 38 so that, while overflow from the tube 9 entering the tube 28 is arrested by the baffle 37, the liquid and materials carried thereby may find ready escape between the baffle and the inner wall of the tube 28.

The three tubes 28, 29 and 30 have interior helical ribs 39, 40 and 41, respectively. These ribs are all similar to the ribs 20 of the tube 9 and are triplicate ribs having the same spacing and pitch in all the tubes. However, the pitch of the ribs 39 is opposite to that of the ribs 20, the pitch of the ribs 40 is opposite to that of the ribs 39 and consequently corresponds to the direction of pitch of the ribs 20, while the pitch of the ribs 41 is opposite to that of the ribs 40. Consequently, with the tubes all rotating in the same direction concentrates engaged by the ribs 20 in the tube 9 are caused to travel up the tube to the upper discharge end thereof and fall into the concentrate hopper 21. Material escaping over the ledge formed by the flanges 31 and 33 is received into the tube 28 and the precipitates are engaged by the ribs 39 and are caused to travel lengthwise of the tube 28 to that end thereof remote from the tube 9 where the precipitates fall from the end of the tube, which is open, and fall into the tube 29 and are carried by the ribs 40 toward the tube 9 to be discharged adjacent to the tube 9 into the corresponding end of the tube 30. What heavy materials there may be are carried by the ribs 41 along the tube 30 to the discharge end thereof, falling from this tube into the tank 5 and into a hopper 42 communicating with and depending from the tank 5 beneath the discharge end of the tube 30, from which such heavy matter constituting tailings may be withdrawn from time to time by opening a gate 43 provided for the purpose.

On the exterior of the tube 30 near opposite ends thereof are annular ribs 44 engaged by rollers 45 similar to the rollers 11, such rollers sustaining the tube 30 near opposite ends thereof and the ribs 44 and rollers 45 preventing longitudinal movements of the tube 30. At the end of the

tube 30 near the tube 9 is an annular series of gear teeth 46 by means of which rotary motion may be imparted to the tube 30 by any suitable gear train, which latter, however, is not shown.

- 5 The end of the tube 30 toward the tube 9 is provided with an interior annular flange 47 preventing the escape of precipitates from the corresponding end of the tube 10 while the other end of the tube is freely open to permit the final escape of the tailings to the hopper 42. That end of the tube 29 adjacent to the hopper 42 is provided with an inner annular flange 48, not only 15 preventing the escape of tailings deposited into the corresponding end of the tube 29 by the tube 28 but serving as a track engaged by grooved rollers 49 carried by spindles 50 fast in and projecting from spacing bars 51 secured to adjacent uprights or posts 20 1 of the main frame. The same spindles 50 carry other rollers 52 entering the corresponding end of the tube 28 and serving as a support therefor upon which the tube 28 25 may rotate.

The rollers 45 are, like the rollers 11, carried by saddles 53 in turn carried by the beams 3 extending lengthwise of the frame and made fast to appropriate parts of the 30 main frame.

Each alternate baffle 7 in the tank 6, constituting a continuation of the tank 5, stops short of the bottom of the tank to provide a passage 55. Those baffles under which are 35 formed the passages 55 extend to a greater height than the remaining baffles which are continued to and join the bottom of the tank 6. In this manner water entering the tank 5 is caused to flow over a baffle, under the 40 next one, over the third one and so on until reaching the overflow 8 which rises to a sufficient height within the tank 6 and from which the water may be directed into a suitable receptacle. The baffle tank 6 causes 45 so slow a flow of water as to give time for the very fine particles to be ultimately deposited in the tank 6 so that the amount of solids ultimately passing through the overflow 8 constitute but a very small fractional 50 part and only the lightest of the materials to be recovered.

The ore used is ground to a suitable fineness sufficient to liberate metal from the quartz or gangue and the metal may be recovered either by flotation or precipitation 55 or both.

In treating certain ores, such as those containing gold, a cyanid solution such as is customarily employed may be used. Since 60 with the use of the apparatus of the invention the separation of solids from the liquid is very thorough, the liquid may be used over and over again, wherefore, there is no waste of chlorid values and it is only when 65 the liquid ultimately becomes too slimy that

it is drawn off into a vat and fresh liquid is turned into the tank 5.

While the tubes are revolving on their roller supports the material to be treated is fed into the tube 9 through the charging 70 hopper 24. Jets of water are played upon the inside of the tube 9 through the perforations in the jet pipe 25, washing the material into and through the tube 9 with the exception of the concentrates which settle 75 to the bottom and are carried back by the ribs or threads in the tube 9 and are discharged into the concentrate hopper 21. The concentrates are ultimately drawn off 80 into a separate tank.

The water level in the flotation tank 5 is about one inch above the bottom of the tube 9 and the water flowing constantly through the tubes carries the flotation toward the baffle tank 6, while tailings settle to the 85 bottom of the tubes, being carried by the threads or ribs in the tubes first to the end of tube 28, then returning through the tube 29 and finally are deposited into the tube 30 and are carried to the discharge end of 90 this tube so that the tailings ultimately fall into the hopper 42 to be finally withdrawn therefrom.

The flotation tank 5 is given a slight slant, say about one inch more or less, toward 95 the discharge end so that the water naturally flows toward said discharge end, ultimately overflowing into the baffle tank carrying the floating material with it. The baffle plates cause so sluggish a flow of water 100 through the baffle tank that floating substances have time to settle. The water finally escapes from the baffle tank through the overflow or decanter tube 8 which may be made adjustable up and down to control 105 the depth of water in the tank 6. The overflow may be collected in still another tank, not shown, and pumped back into the supply tank 4 for reuse.

The concentric tubes 28, 29 and 30 are 110 secured together in diametrically spaced relation by pins or rods 56 which may be located near the ends of the tubes remote from the rollers 49 and 52.

What is claimed is:—

1. In an ore separator, an inclined rotatable concentrating tube, and a horizontal tube forming a continuation of the lower end of the first-named tube and rotatable therewith.

2. In an ore separator, an inclined concentrating tube with interior means for propelling concentrates to the high end of the tube, and a horizontal tube forming a continuation of the lower end of the first-named tube and provided with interior means for propelling material along said second-named tube away from the first-named tube.

3. In an ore separator, an inclined con-

115

120

125

130

- centrating tube having means for feeding ore thereto and means for directing liquid into the tube, another substantially horizontal tube connected to the lower end 5 and forming a continuation of the first-named tube, and a flotation tank into which the second-named tube dips.
4. In an ore separator, an inclined concentrating tube having means for feeding ore thereto and means for directing liquid into the tube, another substantially horizontal tube connected to the lower end and forming a continuation of the first-named tube, and a flotation tank into which the 10 second-named tube dips, the first-named tube having interior means for propelling material therein toward the high end of the tube and the second-named tube having means therein for propelling material toward that end of the tube remote from the first-named tube.
5. In an ore separator, an inclined concentrating tube, a horizontal tube connected to the lower end of and forming a continuation of the inclined tube, other tubes concentric with and spaced from and connected to the second-named tube, and each smaller tube receiving the material at one end and discharging it at the other end into the next 15 larger tube, all the tubes having means therein for propelling material in respectively opposite directions lengthwise of the tubes, and a flotation tank into which the concentrically arranged tubes dip.
6. In an ore separator, a flotation tank, a tube for gathering concentrates located above and dipping at one end into the tank and provided with means for propelling concentrate toward the other end of the 20 tube to discharge therefrom, and a series of concentrically arranged tubes with the innermost one connected to and forming a continuation of the first-named tube, said series of tubes being arranged horizontally and dipping into the flotation tank through their length and also provided with means for propelling material in successively in 25 respectively alternate directions through the concentric tubes.
7. In an ore separator, a flotation tank, a tube for gathering concentrates located above and dipping at one end into the tank and provided with means for propelling concentrates toward the other end of the 30 tube to discharge therefrom, and a series of concentrically arranged tubes with the innermost one connected to and forming a continuation of the first-named tube, said series of tubes being arranged horizontally and dipping into the flotation tank through their length and also provided with means for propelling material in successively in 35 respectively alternate directions through the concentric tubes.
8. In an ore separator, a flotation tank, a tube for gathering concentrates located above and dipping at one end into the tank and provided with means for propelling 40 concentrates toward the other end of the tube to discharge therefrom, and a series of concentrically arranged tubes with the innermost one connected to and forming a continuation of the first-named tube, said series of tubes being arranged horizontally and dipping into the flotation tank through their length and each provided with means 45 for propelling material in a direction opposite to the next larger tube, said flotation tank being provided with a receptacle for concentrates in position to receive from the first-named tube and a receptacle for tailings in position to receive from the last-named tubes, and said flotation tank being provided with a continuation having baffles 50 therein to produce a tortuous passage for liquid received into the continuation from 55 the flotation tank.
9. In an ore separator, a flotation tank, a baffle tank forming a continuation of and receiving from the flotation tank, concentrating means leading into the flotation 60 tank, and tailings-conveying means receiving from the concentrating means and located in the flotation tank.
10. In an ore separator, a flotation tank, a baffle tank forming a continuation of and receiving from the flotation tank, concentrating means leading into the flotation 65 tank, and tailings-conveying means receiving from the concentrating means and located in the flotation tank, said tailings-conveying means having means for directing material back and forth therein while 70 immersed in the flotation tank.
11. In an ore separator, a flotation tank, a baffle tank forming a continuation of and receiving from the flotation tank, an inclined rotatable concentrating tube associated with the flotation tank and dipping 75 at the low end into said tank, said concentrating tube having means therein for propelling concentrates toward the high end of the tube to discharge therefrom, and a plurality of rotatable concentric horizontal tubes dipping throughout their length in the flotation tank, said plurality of tubes having 80 interior means for propelling material therein lengthwise of the tubes and in a direction opposite to the propelling means of the neighboring tube, and the inner one of the concentric tubes constituting a continuation of the inclined tube, and its material propelling means working oppositely 85 to the material propelling means of the first-named tube.
12. In an ore separator, a rotatable in- 90

clined concentrating tube, a horizontal tube forming a continuation of the inclined tube and receiving from the lower end of the latter, and means for varying the inclination of the inclined tube.

13. In an ore separator, a rotatable inclined concentrating tube, a horizontal tube forming a continuation of the inclined tube and receiving from the lower end of the latter, and means for varying the inclination of the inclined tube, said means comprising a pivoted support for the lower end of the inclined tube with the pivotal axis near the top portion of the tube, and adjusting means carrying the high end of the tube.

14. In an ore separator, an inclined rotatable concentrating tube, and a horizontal rotatable tube forming a continuation of the inclined tube and receiving therefrom, said inclined tube having a neck entering the horizontal tube and said horizontal tube having a baffle adjacent to the neck in the path of material discharged from the neck.

15. In an ore separator, an inclined rotatable concentrating tube, a horizontal rotatable tube forming a continuation of and receiving from the lower end of the inclined tube, and a slidable driving connection between the two tubes where meeting, whereby to compensate for the angular relation of the axes of rotation of the two tubes and to transmit rotative movement from one tube to the other.

16. In an ore separator, a main frame, an inclined supplemental frame pivotally hung at one end and at the other end provided with adjustable means connected to the main frame for varying the tip of the supplemental frame, rollers carried by the supplemental frame, and a rotatable tube carried by the rollers and provided with means for causing material within the tube to be propelled toward the high end of the latter.

17. In an ore separator, a main frame, an inclined supplemental frame pivotally hung at one end and at the other end provided with adjustable means connected to the main frame for varying the tip of the supplemental frame, rollers carried by the supplemental frame, and a rotatable tube carried by the rollers and provided with means for causing material within the tube to be propelled toward the high end of the latter, said tube having means for feeding ore thereto, and a jet pipe extending lengthwise of the tube for directing liquid upon ore deposited in the tube.

18. In an ore separator, a rotatable inclined concentrating tube, a flotation tank

into which the lower end of the tube dips, and a plurality of substantially horizontal rotatable tubes also dipping into the flotation tank and in concentric relation to each other with the innermost tube constituting a continuation of the concentrating tube and connected thereto, all the tubes having interior helical ribs with the trend of the ribs of each tube opposite to that of the next tube in order.

19. In an ore separator, a rotatable concentrating tube provided with a continuation, the concentrating tube having interior means for propelling material therein toward the end of the tube remote from the continuation and said continuation having interior means for propelling material toward the end of the continuation remote from the concentrating tube.

20. In an ore separator, a rotatable concentrating tube for receiving material at one end and delivering it at the other end and provided with interior means for propelling concentrates toward the receiving end of the tube, and another tube forming a continuation of the first-named tube and rotatable therewith and provided with interior means for propelling material received from the first tube toward the end of the second tube remote from the first tube.

21. In an ore separator, a series of concentric tubes each having interior means for propelling material therethrough in succession with the direction of propulsion in each succeeding tube opposite to that of the preceding tube.

22. In an ore separator, a series of concentric tubes in diametrically spaced relation, each tube having interior means for propelling material therein from one end toward the other, the direction of action of the propelling means being opposite in each tube from the action of the propelling means in the next tube in order.

23. In an ore separator, a series of three concentric tubes in diametrically spaced relation, each tube having helically arranged means for propelling material deposited in the tube from one end thereof toward the other, the trend of the propelling means in each tube being opposite to the trend of the propelling means in the next tube in order.

In testimony, that I claim the foregoing as my own, I have hereto affixed my signature.

JOHN E. ARMITSTEAD.
